UNITED STATES PATENT OFFICE.

EMILE RIMAILHO, OF PARIS, FRANCE, ASSIGNOR TO COMPAGNIE DES FORGES ET ACIERIES DE LA MARINE ET D'HOMECOURT, OF PARIS, FRANCE.

WHEELED GUN-CARRIAGE.

1,330,614.

Specification of Letters Patent.

Patented Feb. 10, 1920.

Original application filed May 26, 1917, Serial No. 171,207. Divided and this application filed October 22, 1918. Serial No. 259,205.

To all whom it may concern:

Be it known that I, EMILE RIMAILHO, a citizen of France, residing in Paris, France, have invented a new and Improved Wheeled 5 Gun-Carriage, of which the following is a full, clear, and exact description.

My invention relates to wheeled gun carriages, and has reference more particularly to the trail construction of the carriage, 10 forming a divisional matter of my application, Serial No. 171,207 filed May 26, 1917.

The object of the present invention is the construction of a gun carriage in which the front part of the trail system is provided 15 with extensions.

On the drawings annexed—

Figure 1 is a plan of the gun carriage, the trails being open and extended for firing, a portion of the structure being broken out to 20 show the details of construction; and

Figs. 2 and 3 are similar views of carriages showing a modified construction of the trails.

As the gun carriage which we are considering must, with a view to road service, exhibit the usual arrangement of a carriage with single central trail, these trails have been designed according to the arrangement shown on the drawings. The male part 1 of a ball and socket joint is fixedly connected to the trail frame 22. This trail frame is in 25 the shape of a V or a horse shoe, the branches 23 of which have sockets for trail beams, marked 6 and 7, in which said beams are free 30 to slide. The trail beams have a pivotal connection with the branches 23 through the medium of a link 34. The link has a pivotal connection with a branch 23 and with a beam. The links, beams, and branches 23 35 have openings adapted to register when the trail beams form a continuation of the branches 23, these openings being engageable by bolts 40. See position shown in full lines in Fig. 1. The trail beams in that position have a contact with the lateral wall 24 in the enlarged end of the socket of the branches 23.

The road position of the trail is indicated in dotted lines in Fig. 1. To bring the trail beams into said position, the bolts 40 must be removed, when the trail beams 6 and 7 can be swung on their pivots 2, which is permitted by the enlarged sockets 3 of the extensions 23. The trail beams can then be

pushed toward the axle to bring the openings in the end thereof for the bolts 40 in register with the openings of extensions 38 of the axle and secured thereto by pins 36. When the trail beams are so connected, the butts of the trails will come in contact on 60 the longitudinal axis of the carriage and may be bolted by any suitable device.

In the modified form shown in Fig. 2, the ends of the trail beams at the links 34 swing inwardly. The passage for the ends of the 65 trail beams is formed in the upper part of the branches 23 to bring the ends of said trail beams into engagement with the extensions 37 and the axle to which they may be secured. In this construction the enlarged 70 sockets 3 of the extensions are eliminated, and the construction permits a greater shortening of the trail in the folded or road position.

In the modification shown in Fig. 3, the 75 branches 23' have a brace 4 to which the ends of the trail beams 6 and 7 may be connected. For this purpose, openings are provided in the brace 4 with which the end openings of the trail beams may register when they fold 80 against one another, as shown in full line in Fig. 3, the dotted lines indicating the firing position. The contact of the trail beams 6 and 7 allow for road transit a greater angle 85 for the degree of turn which the limber may make.

I claim:

1. A wheeled gun carriage comprising an axle frame, a trail frame, a pivoted connection between the axle frame and the trail frame, trail beams having slidable engagement with the trail frame, links connecting the trail frame and beams, means for locking the links to the trail frame and beams to hold the trail beams diverging, and means for locking the trail beams to the axle frame to hold them converging. 90

2. A wheeled gun carriage comprising an axle frame, a trail frame pivotally mounted on the axle frame, trail beams, links pivotally connecting the beams to the trail frame so that said beams may form extensions of the trail frame or be connected to the axle frame, and means for locking said beams to either the trail frame or the axle frame. 100

3. A wheeled gun carriage comprising an axle wheel frame, a V-shaped trail frame pivotally connected to the axle frame, trail

beams, links, means connecting pivotally the ends of the links between the ends of the branches of the V-shaped trail frame and between the ends of the beams whereby the 5 ends of the beams may be brought into engagement with the ends of the V-shaped trail frame, said beams, branches and links having openings adapted to register when said links, branches and beams are in alinement, means for engaging said registering 10 openings, and means for connecting the ends

of the beams to the axle frame when said beams are swung on the links to converge.

4. A wheeled gun carriage comprising an axle frame, a trail frame pivotally mounted on the axle frame, trail beams, links pivotally connecting the trail beams and the trail frame so that said beams may diverge or converge, and means for locking said beams in diverging or converging position. 15 20

EMILE RIMAILHO. [L.S.]
